UNITED STATES PATENT OFFICE.

WILLIAM M. SMITH, OF MERIDEN, CONNECTICUT, ASSIGNOR TO THE MERIDEN BRITANNIA COMPANY, OF SAME PLACE.

DESIGN FOR A COFFIN-SCREW.

SPECIFICATION forming part of Design No. 15,044, dated June 3, 1884.

Application filed March 17, 1884. Term of patent 14 years.

To all whom it may concern:

Be it known that I, WM. M. SMITH, of Meriden, in the county of New Haven and State of Connecticut, have invented a new 5 Design for Coffin-Screws; and I do hereby declare the following, when taken in connection with accompanying drawings and the letters of reference marked thereon, to be a full, clear, and exact description of the same, and which 10 said drawings constitute part of this specification, and represent, in—

Figure 1, a front perspective view looking downward; Fig. 2, a transverse vertical central section; Fig. 3, a horizontal section taken at the 15 point where the side curves meet the segment.

This invention relates to an improvement in design for the heads of that class of screws commonly called "coffin-screws;" and the design consists in the configuration of the head, 20 as shown in the accompanying illustration and hereinafter described.

From the base *a* the head rises. In horizontal transverse section it is of substantially double convex shape, as seen in Fig. 3. In 25 vertical transverse section it contracts from

the base into such double convex shape as seen in Fig. 2. In face view the sides curve upward and outward, the tip in the shape of a segment of a circle the crowning side up, the ends of the segment meeting the ends of the 30 said curves, as shown in the accompanying illustration. The faces of the tip portion represent a fan-shaped ornament, with bands below extending from edge to edge.

I claim—

The design for a coffin-screw, consisting of a base, the head rising therefrom substantially concavo-convex in horizontal transverse section, in face view the two sides curved upward and outward, the tip in the form of a 40 segment of a circle crowning side up, the ends of the segment meeting the curves of the two sides, the faces of the tip representing a fan-shaped ornamentation, as shown in the accompanying illustration.

WILLIAM M. SMITH.
